FRANK T. JONES, OF BALTIMORE, MARYLAND, ASSIGNOR TO THE JONES SAFETY TRAIN CONTROL SYSTEM COMPANY, OF BALTIMORE, MARYLAND, A CORPORATION OF MARYLAND.

ELECTRIC TRAIN-CONTROLLED SYSTEM FOR RAILWAYS.

1,072,383.

Specification of Letters Patent.

Patented Sept. 2, 1913.

Application filed July 5, 1910. Serial No. 570,329.

To all whom it may concern:

Be it known that I, FRANK T. JONES, a citizen of the United States, residing at Baltimore, in the State of Maryland, have 5 invented certain new and useful Improvements in Electric Train-Controlled Systems for Railways, of which the following is a specification.

This invention relates to an improved arrangement for a block system train control for railways and has for its object to provide an improved arrangement of circuits whereby to operate certain devices and instrumentalities on a train when the latter 15 approaches a block already occupied by a train, as will presently more fully appear.

The invention is illustrated in the accompany drawing, in which,

Figure 1 is a diagrammatic illustration of 20 the trackway and the improved arrangement of circuits employed in connection therewith and shows the devices in position to protect the rear of a train. Fig. 2 is a similar view showing the position of the 25 devices when trains are approaching each other.

In carrying out the invention I provide the rails, 1, and, 2, with a plurality of insulating members, 3, to effect an electrical 30 separation and produce a series of sections, which we designate, 4, 5, 6, 7, 8, 9 and, 10, in the drawing, Figs. 1 and 2. In the present instance the several sections are not all of the same length,—the sections, 4, 6, 8, 35 and, 10, being somewhat longer than the intervening sections, 5, 7, and, 9, but this is not essential to the invention.

In the present invention I propose to control the movement of trains in both directions and keep them sufficiently separated by giving a caution signal first to both in case they approach from opposite directions and to the rear train if both are traveling in the same direction and then in case they 45 continue to approach each other to stop both trains or in case one approaches the other to stop the rear train.

In carrying out my invention I employ a closed circuit system so that the system will 50 be maintained in the operative condition only so long as the circuits are maintained, and will give caution signals, and stop the

trains if the circuits become interrupted or broken regardless of whether the track is clear or not.

55

By reference to Fig. 1, it will be noted that at the outer side of rail, 1, the section, 4, is provided with a short rail section, 11, which for the purpose of the present case will be termed the signal rail or section. An 60 electro-magnet, 12, is provided adjacent the said signal rail-section and said magnet has an armature, 13, the pivot-end of which is electrically connected to one side of a battery, 14, by wire, 15. Another wire, 16, extends from the other side of battery, 14, to and is connected to rail, 1, while said signal-rail, 11, has a wire, 17, that by contact with the free end of armature, 13, when the latter is attracted by electro-magnet, 12, will throw 70 said signal-rail, 11, into the circuit of battery, 14, as long as electro-magnet, 12, is maintained in an energized condition. The energization of this electro-magnet, 12, is effected by means of a main track circuit 75 from one of the main track-way sections some distance ahead,—for example, the electro-magnet, 12, at the side of main rail, 1, of section, 4, is energized by current passing through line, 18, that extends from said 80 magnet indirectly to the line, 19, that connects with rail, 1, in section, 9,—thus it will be seen that several sections intervene between the point where the signal is to be given at section, 4, and the point from which 85 the signal device is to be controlled. The current for maintaining the said magnet, 12, of section, 4, is derived from a battery, 20, that has its opposite sides connected by wires, 21, and, 22, to the main track rails, 1, 90 and, 2, in said section, 9. A ground connection, 23, is provided for section, 9, and another ground connection, 24, is provided beyond magnet, 12, of section, 4, by means of which two ground connections, the circuit 95 from battery, 20, of section, 9, to electro-magnet, 12, of section, 4, is maintained, while the intervening track-way and sections are clear. But in the instance illustrated in Fig. 1, it will be seen that a train 100 or vehicle, 25, has entered the section, 8, and is assumed to be traveling toward section, 9, and the presence of this vehicle requires that devices somewhere at the rear be set to

give a caution signal for a train following in the rear of train, 25. For this reason, it will be noted that the armature, 13, adjacent rail, 1, of section, 4, has dropped because the electro-magnet, 12, that normally holds it has become deenergized, and consequently signal rail, 11, is out of circuit with battery, 14. This deenergization of magnet, 12, is brought about by an interruption of the circuit somewhere between the vehicle, 25, and the magnet, 12, of section, 4, at the rear of the vehicle and it will be noted that the interruption which has taken place has been caused by the deenergization of another 15 electro-magnet, 26, whose armature, 27, normally forms a connection between lines, 18, and, 19. The deenergization of this magnet, 26, in the instance illustrated in Fig. 1, has been caused by the presence of the train, 25, in section, 8, because the current from battery, 28, in said section, 8, instead of passing by wires, 29, and, 30, of rails, 1, and, 2, to magnet, 26, has been short-circuited through the vehicle and is in this instance 25 from said battery, 28, to rail, 1; through the wheels and axle of train, 25, to rail, 2, and then back to the battery. Thus it will be seen that the presence of the train in section, 8, will cause the caution signal rail, 11, in 30 the rear of the train and in the instance cited at section, 4, to be cut off from battery, 14, by breaking the circuit in the line, 19—18 that leads to magnet, 12, thus deenergizing magnet, 12, and allowing armature, 13, to drop. A caution signal rail in advance of 35 the section, 8, will likewise be effected by the deenergization of the same electro-magnet, 26, through the dropping away of a second armature, 31, which normally engages or electrically connects track-wire, 32, from rail, 1, of section, 7, with wire, 33, that leads indirectly to an electro-magnet several 40 sections ahead that actuates an armature to supply current to a signal rail ahead of the 45 approaching train. Thus it will be understood that caution signal-rails both at the rear and ahead of a train are affected by the moving train between them.

In addition to the caution signal-rail, 11, 50 above described in connection with track-way section, 4, it will be understood that other sections,—for example, sections, 6, 8, and, 10, are also provided with like signal rails and with magnets, armatures and batteries to coact therewith, and all of said devices have the same function to give caution 55 signals on trains traveling in the direction from sections, 4, toward, 10, and onward and are operated precisely as has been described 60 with respect to rail, 11, at section, 4; consequently it is deemed unnecessary to repeat the description for these various signal rails.

In case a train, after receiving the caution 65 signal at section, 4, should proceed into sec-

tion, 5, while train, 25, is still in section 8, I have provided means whereby to interrupt certain circuits to effect a complete stoppage of the rear train and to this end I have provided at said section, 5, a stop-rail, 34, 70 at the outer side of track rail, 1, which stop-rail is provided with a wire or line, 35, that terminates adjacent an armature, 36, which is actuated by an electro-magnet, 37, that is included in the circuit comprising wire, 18, 75 armature, 27, wire 19, and the tracks 1, and, 2 of section, 9, which is the same circuit that normally energizes electro-magnet, 12, of section, 4. Thus it will be seen that when train, 25, interrupts the circuit through 80 wires, 29, and, 30, and deenergizes electro-magnet, 26, the falling away of armature, 27, will serve to deenergize magnet, 37, and allow armature, 36, thereof to break connection with wire or line, 35, to stop-rail, 34. 85 The armature, 36, is connected at its pivot-end through a second armature, 38, and by wire, 39, to one side of a battery, 40, while the other side of said battery is in electrical connection with track rail, 1, by means of wire, 41, when the road ahead of section, 5, is clear for a train to pass through said section. But in the example shown in Fig. 1 of the drawing the position of train, 25, in block, 8, has effected a break in the track 90 circuit from section, 9, through armature, 27, and wire, 18, and all magnets included in that circuit of which magnet, 37, is one, are shown as deenergized and consequently armature, 36, is down and has broken the 95 circuit from battery, 40, to stop rail, 34, and the result is that a contact shoe on a train when reaching said rail, 34, cannot pick up the circuit from battery, 40, to maintain the 100 brake apparatus in the cut off or safety position as will presently be explained, and the brakes would be applied to effect a stoppage of the train in the rear of train, 25. Now by reference to Fig. 2, of the drawings it will be noted that a vehicle or train, 43, is 105 located in section, 10, while another vehicle or train, 44, has entered section, 5, and both vehicles are presumed to be traveling toward each other. The vehicle, 43, has short-circuited the current from battery, 45, of section, 10, and consequently magnet, 46, has 110 been deenergized because wires, 47, and, 48, are cut off by vehicle, 43, from battery 45. Armatures, 49, and, 50, have dropped from magnet, 46, and track current that before 120 passed through wires, 51, and, 52, will be broken, thus deenergizing electro-magnets, 53, 54, and, 55, all of which are included in the line or wire, 56. The deenergization of magnet, 55, will cut-off signal rail, 57, from 125 battery, 58, because of the dropping of armature, 59, while the deenergization of magnet, 54, will cut-off stop rail, 60, from battery, 61. Thus neither the rail, 57, or the rail, 60, will have any current to pass to the 130

vehicle, 44, when the shoes of the latter pass over those rails and that vehicle would first receive the signal and then the stop if it continued toward vehicle, 43. On the other hand, the presence of vehicle, 44, in section, 5, will short-circuit the current from battery, 62, in said section, 5, and as no current will pass through line or wire, 63, armature, 64, and wire, 65, electro-magnets, 66, 67, 10 and, 68, immediately in front of vehicle, 43, will become deenergized and allow their armatures, 69, 70, and, 71, to drop. The dropping of armature, 71, will cut off signal-rail, 72, from battery, 73, and the dropping 15 of armature, 70, will cut off stop rail, 74, from battery, 75, thus the presence of vehicle, 44, in section, 5, will effect a cutting off of current to both rails, 72, and, 74, adjacent sections, 10, and, 9, and will thereby 20 first signal vehicle, 43, and then stop said vehicle if it attempts to proceed past stop rail, 74, adjacent section, 9. Thus it will be seen that vehicle, 44, moving in one direction will signal the vehicle, 43, approaching 25 it from in front when the latter reaches section, 10, and will stop said vehicle, 43, before it passes out of section, 9, while vehicle, 43, will signal vehicle, 44, at section, 6, and stop it at section, 7. It will also be understood 30 that both vehicles will operate to give signals and effect the stoppage of trains approaching from the rear as described in connection with Fig. 1 of the drawing.

The devices carried on the vehicle to first 35 signal the engineer in case of danger ahead and to effect an operation of the air-brakes in case the engineer takes his train into another section regardless of the warning signal previously given him, may vary in construction, but an example of the same may 40 be seen in the pending application Serial Number 562,986 of R. T. and F. T. Jones filed May 23rd, 1910.

The vehicle travels over the rails 1 and 2 45 and has a signal-contact shoe or brush, 85, which successively brushes over and makes contact with ramp or short rail sections along the track and is also provided with another shoe or brush, 113, which contacts 50 with other ramp or short rail sections, 34, which are herein referred to as stop rails and which are also located along the track. One of these brushes is electrically connected 55 with suitable mechanism on the vehicle for giving a warning signal while the other is electrically connected with mechanism on the vehicle for setting the brakes.

It is to be understood that signal and stop 60 rails for the various track sections for trains or vehicles traveling in one direction are located at one side of the trackway while those for trains or vehicles traveling in a reverse direction are arranged at the opposite side of said tracking.

Having thus described my invention what

I claim and desire to secure by Letters Patent is,—

1. In a trackway train controlling mechanism for railways the combination with the two track rails each provided at intervals with insulation to form a series of stop-train track-sections, of a constant current supply for each stop-train track-section; a short stop-rail extending parallel with and adjacent to each stop-train track-section; a local current supply for each of said short stop rails; a pair of armatures interposed between each stop rail and its local current supply; a pair of electro-magnets for each pair of armatures,—one magnet being provided for one armature and the other magnet for the other of said pair of armatures; a circuit for one magnet of each pair including the track rail and the current supply for one section ahead to energize said magnet and hold one of the said two armatures, and another circuit for the other magnet of each pair including the track rail and the current supply of a different track-section to hold the said other of the two armatures whereby the energization of both electro-magnets will attract both said armatures and maintain a connection from one side of a short stop rail and its local current supply.

2. In a trackway train controlling mechanism for railways the combination with the track rails insulated from each other at intervals to form a series of electrically independent track sections including both track rails, of a separate current supply for each of said sections; a short signal rail adjacent every other track section and extending parallel with the track rails; short stop rails adjacent those track sections that intervene between the sections to which the signal rails are adjacent,—said signal and stop rails being out of alignment with each other; a separate local current supply for each short signal rail; a separate current supply for each short stop rail; connections between each short rail and its particular current supply; an armature interposed in each of said connections between said short rails and their respective current supplies; an electro-magnet for each armature and circuits each including the two rails of a track section and their source of current supply, said circuits also including an electro-magnet that controls an armature between one stop rail and its current supply, and another electro-magnet that controls an armature between one signal rail and its current supply, to normally energize said electro-magnets and keep a short stop rail and a short signal rail in electrical connection with their respective current supplies when the track is clear.

3. In a trackway train controlling mechanism for railways the combination with the rails insulated from each other at intervals to form a series of track sections including

both track rails, of an independent current supply for each track section; a short signal rail for and adjacent every other track section; a local current supply for each signal rail; connections between each signal rail and its local current supply,—said connections each including an armature; a magnet for actuating each of the same; a stop rail adjacent those track rails that intervene between those sections to which the signal rails are adjacent,—said stop and signal rails being out of alinement; a local current supply for each stop rail; connections between each stop rail and its local current supply and said latter connections each including an armature; a magnet for actuating each of

the same, and connections from a current supply of a track-section ahead including an electro-magnet that actuates an armature between a signal-rail and its current supply and an electro-magnet with its armature between a stop-rail and its current supply whereby to normally energize said magnets and maintain the armature connections between said signal and stop-rails and their respective current supplies.

In testimony whereof I affix my signature in presence of two witnesses.

FRANK T. JONES.
